ATTORNEY.

UNITED STATES PATENT OFFICE.

JOHN S. DOVE, JR., OF PHILADELPHIA, PENNSYLVANIA.

TYPE-WRITING MACHINE.

SPECIFICATION forming part of Letters Patent No. 398,587, dated February 26, 1889.

Application filed August 13, 1886. Serial No. 210,782. (No model.)

To all whom it may concern:

Be it known that I, JOHN S. DOVE, Jr., a citizen of the United States, residing in the city and county of Philadelphia and State of Pennsylvania, have invented a new and useful Improvement in Type-Writing Machines, which improvement is fully set forth in the following specification and accompanying drawings, in which—

10 Figure 1 represents a vertical section of a portion of a type-writing machine embodying my invention. Fig. 2 represents a front view thereof. Fig. 3 represents an enlarged view of the guide with adjustable buffers shown 15 in Figs. 1 and 2.

Similar letters of reference indicate corresponding parts in all the figures.

My invention relates to improvements in type-writers; and it consists of mechanism, as 20 herein described and claimed, whereby the upper-case and spacing levers may be operated by the foot. By these means the hands are free to operate the several type-keys without being required to depress or manipulate 25 the key of the upper-case lever or the bar of the spacing-levers.

Referring to the drawings, A represents a table for supporting a type-writing machine, which, excepting some slight changes necessary to adapt it to my invention, may be of well-known construction—such as, for instance, that of the Remington—to which, however, I do not limit the invention.

B represents the key of the upper-case lever 35 C, and D represents the connecting-bar of the spacing-levers E, said levers having connected with them depending rods F F', which pass through openings in the table A, and are attached to levers G G', which are mounted on 40 hangers or ears G² on the under side of the table. The levers G G' are connected by links or straps with levers H H', which are mounted on hangers or ears H² on the under side of the table. The levers H H' are connected by means 45 of rods J J' with foot-treadles K K', the latter being mounted on a rod, L, which is attached to the legs of the table at the lower end thereof.

It will be seen that when it is desired to operate the upper-case lever C the treadle K 50 is moved by the foot, whereby, by means of the rod J, lever H, lever G, and rod F, said lever is depressed, and the hand thus relieved from striking the key B. When it is desired to operate the spacing-levers E, the treadle K' 55 is moved by the foot, whereby, by means of the rod J', lever H', lever G', and rod F', said levers are depressed, and thus the hand is relieved from striking the spacing-bar D.

The parts are restored to their normal positions by means of springs J², which are attached to the connecting bars or rods J J' and under side of the table. The springs are preferably connected to the bars J J' by means of an adjustable sleeve, R, on each of said 65 bars, which sleeve is secured thereon by the screw S, as shown in the drawings.

The levers H H' pass through slotted guides M, which depend from the table A, and contain buffers N, of rubber or other elastic or flexible material, said buffers being above and below the respective levers H H', and attached to screws P, which are fitted to cross-bars in said guides, whereby the buffers may be set with nicety in relation to the throw of 75 the levers H H', the object of said buffers being to stop or limit the motions of the levers H H', thus preventing strain on the levers C E and also obviating noise when the levers H H' strike said stops.

Having thus described my invention, what I claim as new, and desire to secure by Letters Patent, is—

In a type-writing machine, an upper-case lever, in combination with a foot-treadle and 85 intermediate depending rod, levers, and connecting-rod, one of said intermediate levers having a guide with buffers, all substantially as and for the purpose set forth.

JOHN S. DOVE, JR.
